HAROLD P. HASTINGS AND JOHN J. DOSSERT, OF SYRACUSE, NEW YORK, ASSIGNEES
TO CROUSE-HINDS COMPANY, OF SYRACUSE, NEW YORK, A CORPORATION OF NEW
YORK.

ELECTRICAL APPLIANCE.

1,345,768.

Specification of Letters Patent.

Patented July 6, 1920.

Application filed June 24, 1918. Serial No. 241,560.

To all whom it may concern:

Be it known that we, HAROLD P. HASTINGS and JOHN J. DOSSERT, of Syracuse, in the county of Onondaga and State of New York, have invented a certain new and useful 5 Electrical Appliance, of which the following is a specification.

This invention has for its object a particularly simple and efficient arrangement 10 of the conductors and binding devices of electrical appliances; and the invention consists in the novel features and in the combinations and constructions hereinafter set forth and claimed.

15 In describing this invention, reference is had to the accompanying drawings in which like characters designate corresponding parts in all the views.

Figure 1 is a plan view of an electrical 20 appliance embodying our invention, the same being shown as mounted upon a conduit outlet box.

Fig. 2 is a sectional view on line 2—2, Fig. 1.

25 Fig. 3 is an inverted plan view of the base of the appliance.

Figs. 4 and 5 are transverse sectional 30 views taken on the plane of line 4—5, Fig. 2, the binding device being shown in its open position in Fig. 4 and in its operative or closed position in Fig. 5.

Fig. 6 is an isometric view of one of the binding devices.

Fig. 7 is a plan view of one of the conductors.

Figs. 8 and 9 are respectively a plan and an elevation of the other conductor.

This electrical appliance comprises generally, a base, terminals carried by the base, 40 conductors connected respectively to the terminals and located on the rear side of the base, and binding devices coacting with the terminals and operable from the front side of the base.

45 1 designates the base which is here shown as elongated in general form and formed with a lamp receptacle 2 having central and outer terminals 3, 4.

The base is also shown as provided with 50 a reduced portion 5 at its inner or rear end which extends into the open side of a conduit outlet box 6. The base is also formed with recesses 7 in its opposite end portions opening through the rear face of the base 55 and with passages 8 opening through the

inner end walls of the recesses and through the outer or front face of the base.

9 and 10 are conductor bars mounted on the rear face of the base and extending lengthwise thereof, the bars 9, 10 extending 60 across the open rear sides of the recesses 7.

The bar 9 is connected to the central terminal 3 by means of a screw 11 and the bar 10 is connected to the outer terminal 4 by means of a screw 12 both of these screws 65 extending into the base from the front side thereof and having their heads exposed at the bottom of the receptacle.

13 are the binding devices which coact respectively with the terminals 9, 10 these 70 binding devices being movable in the recesses 7 and each having a portion 14 underlying the bar 9 or 10 and movable toward and from the lower side of the same, and a portion 15 movable toward and from the 75 top of the recess 7 and extending across the lower end of the passage 8. Each binding device also includes a portion which slides vertically crosswise of the bars 9 or 10. Each binding device is in the general form 80 of a U-shaped clip, the portions 14 and 15 being the opposite branches of the U-shaped formation and the intermediate portion being formed with a slot 16 providing two bars which slide transversely or vertically 85 of the bar 9 or 10. Usually the bar 9 or 10 is notched at 17 for receiving the bars of the U-shaped clip and guiding the clip during its clamping and unclamping movements.

The means for operating the binding devices comprises screws 18 threading through the portions 15 of the U-shaped binding devices and abutting at their lower ends against the upper faces of the bars 9, 10, the screws being operable from the upper 95 side of the base through the passages 8.

In operation, the wires in the outlet box 6 are stripped and the stripped portions 19, Fig. 5 placed over the hook-shaped portions 14 of the binding devices as shown in Fig. 100 5, and the screws are operated to move the binding devices from the position shown in Fig. 4 to that shown in Fig. 5.

Owing to the arrangement of the binding devices and the operating means therefore, electrical connection is readily made with the wires located in the conduit outlet box.

What we claim is:

1. An electrical appliance comprising a 110

- base having recesses opening through its rear face and passages opening into the inner ends of the recesses and through the outer face of the base, conductors mounted 5 on the rear face of the base and extending across the open ends of the recesses respectively, binding devices slideable in the recesses transversely of the conductors and having portions movable toward and from 10 the outer faces of the conductors respectively, the binding devices being guided by the walls of the recesses, and means extending through said passages from the front side of the base and coacting with the binding devices to move the same in the recesses and thereby move said portions toward and from the conductors, substantially as and for the purpose described.
2. An electrical appliance comprising a 20 base, a conductor mounted on the base, a binding device in the form of a U-shaped clip extending transversely relatively to the conductor and having the branches of the U-shaped formation arranged above and below the terminal and the intermediate part thereof extending crosswise of the conductor, and a screw threading through one of the branches of the U-shaped clip and abutting against the opposing side of the conductor, the intermediate part of the U-shaped clip being formed with a slot thereby providing bars at opposite ends of the 25
- 30

U-shaped clip and the conductor being formed with notches for receiving the bars, substantially as and for the purpose de- 35

3. An electrical appliance comprising an elongated base having recesses near its opposite ends opening through its rear face and passages opening into the inner ends 40 of the recesses and through the outer face of the base, conductors mounted on the rear face of the base and extending lengthwise thereof and across the open ends of the recesses respectively, binding devices slideable 45 in the recesses transversely of the conductors and having portions movable toward and from the outer faces of said conductors and portions movable between the inner faces of the conductor and the inner end 50 walls of the recesses, and screws extending into said passages and threading through the portions of the binding devices at the inner ends of the recesses, the screws abutting against the inner faces of the conductors, substantially as and for the purpose specified.

In testimony whereof we have hereunto signed our names at Syracuse, in the county of Onondaga, and State of New York, this 60 17th day of June, 1918.

HAROLD P. HASTINGS.
JOHN J. DOSSERT.
